CLAIM

The ornamental design for a device to control snoring, as shown and described.

DESCRIPTION

FIG. 1 is a right side elevational view of a device to control snoring where the broken lines form no part of the claimed design;

FIG. 2 is a top perspective view thereof;

FIG. 3 is a bottom perspective view thereof;

FIG. 4 is a top plan view of FIG. 2;

FIG. 5 is a left side elevational view thereof;

FIG. 6 is a bottom view thereof;

FIG. 7 is a front view thereof where the broken line forms no part of the claimed design; and,

FIG. 8 is a rear view thereof.
